[57] **CLAIM**

The ornamental design for a badge shield, as shown and described.

DESCRIPTION

FIG. 1 is a front elevational view of a badge shield showing our new design;

FIG. 2 is a right side elevational view, the left side being a mirror image;

FIG. 3 is a rear elevational view thereof; and

FIG. 4 is a sectional view taken along line 4—4 of FIG. 1.
